RAILWAY TRAFFIC CONTROLLING APPARATUS

Original Filed Nov. 23, 1927

UNITED STATES PATENT OFFICE

2,039,616

RAILWAY TRAFFIC CONTROLLING
APPARATUS

Herbert A. Wallace, Edgewood Borough, Pa., assignor to The Union Switch & Signal Company, Swissvale, Pa., a corporation of Pennsylvania

Application November 23, 1927, Serial No. 235,245
Renewed August 4, 1930

40 Claims. (Cl. 246—3)

My invention relates to railway traffic controlling apparatus, and particularly to apparatus adapted for use in a centralized traffic control system for safely controlling traffic governing devices, such as switches and signals, from a remote point. More particularly, my present invention relates to apparatus of the type described in which the traffic governing devices are controlled in accordance with the strength and/or polarity of the controlling currents. One system of this general character is disclosed and claimed in my copending application, Serial No. 125,659, filed July 29, 1926, for Railway traffic controlling apparatus.

I will describe one form of apparatus embodying my invention, and will then point out the novel features thereof in claims.

The accompanying drawing is a diagrammatic view illustrating one form of apparatus embodying my invention.

Referring to the drawing, the reference character W designates a stretch of track connected with the siding X by means of a railway switch A of the usual form. The switch A is operated by a motor M, which, in the form here shown, comprises a field 3 and an armature 4. The switch controls a plurality of contacts which assume different positions in accordance with the position of the switch. Contact 6, for example, is closed only when the switch occupies its normal position, in which it is illustrated in the drawing. Similarly, contact 5 is closed only when the switch occupies its reverse position. Contact 10—11 is closed at all times except when the switch occupies its normal position, and contact 10—12 is closed at all times except when the switch occupies its reverse position. The switch A also controls a plurality of contacts, here shown as two in number, which are successively closed for a brief interval of time as the switch moves from one extreme position to the other. As illustrated in the drawing, when the switch moves from its normal to its reverse position, contact 7—8 is closed for a brief interval of time and then opened. As the movement of the switch continues, contact 7—8 is closed, and this contact is opened again before the switch attains its full reverse position. During movements of the switch from the reverse to the normal position, the contacts 7—8 and 7—9 are successively operated in the reverse order.

The motor M controlling the switch A, is in turn controlled by a polarized relay D. As shown in the drawing, the switch A occupies its normal position and the relay D occupies its normal posi-

tion. If the relay D now becomes energized in the reverse position to swing its contacts to the right, current from batteries E¹ and E² in series, flows from the positive terminal of battery E², through wires 33, 41 and 42, reverse contact 43 of relay D, wire 44, armature 4 of motor M, wire 45, reverse contact 46 of relay D, wire 47, contact 10—12 operated by switch A, wire 48, field 3 of motor M, and wires 49, 50, 51, 52 and 53 to the negative terminal of battery E¹. As a result of the current thus supplied to the motor M, the motor is operated in such direction as to move the switch A to its reverse position. When the switch attains its full reverse position, contact 10—12 is opened, so that the motor circuit is interrupted. In similar manner, if the relay D is restored to its normal position, current from batteries E¹ and E² in series flows from the positive terminal of battery E² through wires 33, 41 and 42, normal contact 46 of relay D, wire 45, armature 4 of motor M, wire 44, normal contact 43 of relay D, wire 106, contact 10—11 operated by switch A, wire 48, field 3 of motor M, and wires 49, 50, 51, 52 and 53, back to battery E¹. The motor then operates to restore the switch to its normal position, whereupon contact 10—11 opens to deenergize the motor M.

The rails 1 and 1^a of the stretch of track W and that portion of the siding X adjacent the switch, are divided from the rest of the track to form an insulated detector track section which is provided with a track battery T and a track relay R to form a track circuit of the usual and well known type.

Associated with relay R is a polarized relay B and a slow-releasing relay C, the control of which relays will appear as the description proceeds.

Traffic over the switch A is governed by a plurality of signals, each designated by the reference character S, with an appropriate distinguishing exponent. In the present embodiment of my invention, the signal S¹ comprises an upper blade, which may be cleared to indicate to eastbound traffic that the switch A occupies its normal position, and a lower blade, which may be cleared to indicate to eastbound traffic that the switch A is reversed. When signal S¹ is cleared, it indicates that switch A is normal to permit westbound traffic along the stretch W. When signal S² is cleared, it indicated that switch A is reversed to permit westbound traffic from the siding X to enter the stretch W.

The switch A and the signals associated therewith, are controlled by a polarized control relay

G, which, in turn, may be controlled over line wires 17 and 32 from a point remote from the switch, such, for example, as a dispatcher's office or an interlocking cabin. Located in this office or cabin is a signal transmitter including a manually operable circuit controller or lever L, having two normal contacts 13—13^a and 14—14^a closed when the lever occupies one extreme position, two reverse contacts 13—13^b and 14—14^b closed when the lever occupies the other extreme position, and two neutral contacts 13—13^c and 14—14^c closed when the lever occupies its mid-position. Lever L may be one of a plurality of similar levers located in an interlocking machine 15 of the standard type.

Associated with lever L is a manually operable circuit controller K and a stick relay J, the purpose of which will be explained in detail hereinafter. Located adjacent the lever L is a slow-releasing indication relay H, which is controlled to give the operator a return indication of the condition of the apparatus adjacent the switch A.

As shown in the drawing, the switch A occupies its normal position, and the signals S are all at stop. Relay R is energized, relays B and D are de-energized, and relay C is energized. Relays G, H and J, are also de-energized. It should be pointed out that in the case of each of the polarized relays the polar contact which was last closed by positive operation of the relay remains closed until the polar armature is positively swung in the opposite direction. If the operator wishes to reverse the switch A, he moves the lever L to its reverse position, thereby closing contacts 13—13^b and 14—14^b. Current then flows from battery F¹, through wire 15, contact 14—14^b of lever L, wire 16, winding of relay H, wires 17 and 18, winding of relay G, wires 19 and 20, back contact 21 of relay B, wires 22, 23, 24, 32 and 25, reverse contact 13—13^b of lever L, wire 26, winding of relay J, wires 27, 28 and 29, manually operable circuit controller K, and wires 30 and 31, back to battery F¹. The current supplied over this circuit traverses relays J, H and G in series, and the parts are so proportioned that the current supplied by battery F¹ is of sufficient magnitude to energize relay G in the reverse direction, thereby swinging its polar contacts to the right. The current thus supplied to the circuit is not of sufficient magnitude to energize relay H, and this relay therefore remains open. Relay J becomes energized, but this operation has no significance in the sequence of operations about to be traced. When relay G becomes energized in the reverse direction, current from battery E² flows through wires 33 and 34, reverse contact 35 of relay G, wire 36, front contact 37 of relay G, wire 38, winding of relay D, and wires 39 and 40, back to battery E². The current thus supplied to relay D energizes this relay in the reverse direction, thereby setting the motor M into operation to reverse switch A.

During this movement of the switch A, contact 7—9 becomes closed and current then flows from battery E² through wires 33, 41, 54 and 55, contact 7—9, wire 56, front contact 57 of relay R, wires 58 and 59, winding of relay B, and wires 60, 61 and 40, back to battery E². Relay B therefore becomes energized in the normal direction, but relay C is normally held closed by a circuit which passes from battery E¹, through wires 40 and 67, back contact 68 of relay B, wire 69, winding of relay C, and wires 70, 52 and 53 back to battery E¹. The energization of relay B therefore de-energizes relay C. Due to the slow re-

leasing characteristics of relay C, a brief interval of time elapses after the energization of relay B and prior to the opening of front contacts on relay C. During this brief time interval that relays B and C are closed an impulse of energy is delivered to relay H from batteries E¹ and E² in series, the circuit for this impulse of energy passing from battery E², through wires 33, 41, 54 and 55, contact 7—9, wire 56, front contact 57 of relay R, wires 58 and 62, front contact 63 of relay B, wire 64, front contact 65 of relay C, wires 66 and 17, winding of relay H, wire 16, contact 14—14^b of lever L, wire 15, battery F¹, wires 31 and 30, circuit controller K, wires 29, 28 and 27, winding of relay J, wire 26, contact 13—13^b of lever L, wires 25, 32, 24 and 23, normal contact 71 of relay B, and wires 72, 51, 52 and 53 back to battery E¹.

It will be seen that the current thus supplied to relay H traverses battery F¹ in a direction contrary to the electromotive force of this battery. The combined voltage of batteries E¹ and E² is high enough, however, to insure that the current supplied to relay H in opposition to the current supplied by battery F¹ over the circuit just traced is sufficient to energize relay H in the reverse direction so that its contacts swing to the right. When this happens, current from battery P flows over a front contact 87 and reverse contact 88 of relay H to an indication device, here shown as an electric lamp 90. The closing of contact 7—9 by switch A therefore energizes lamp 90 to inform the operator of the lever L that a switch movement has commenced. Of course, contact 7—9 is closed only for a brief interval, and after the expiration of this interval relay B again drops and relay C picks up. Relay H therefore becomes de-energized and lamp 90 is extinguished. When contact 7—8 is closed, however, the same sequence of operations is carried on as has already been described for the closing of contacts 7—9, contact 7—8 being connected in parallel with contacts 7—9. The effect of the return indication given by the apparatus is therefore to flash lamp 90 twice to inform the operator that the switch is being reversed.

When the switch has attained its full reverse position, the opening of contact 10—12 interrupts the circuit for the motor, as explained hereinbefore. The lever L may then be restored to its neutral position to allow relay G to become de-energized. If, however, relay G is held energized in its reverse position, the closing of contact 5 upon movement of the switch to its full reverse position completes clearing circuits for the lower blade of signal S¹ and for signal S². The circuit for signal S² may be traced from battery E², through wires 33, 41, 54 and 73, front contact 74 of relay R, wire 75, front contact 76 of relay G, wire 77, reverse contact 78 of relay G, wire 79, contact 5 operated by switch A, wires 80 and 81, operating mechanism of signal S² and wires 82, 83, 61 and 40, back to battery E². The circuit just traced is provided with a branch which passes from wire 80, through wire 84, operating mechanism of the lower blade of signal S¹ and wire 85 to wire 83. It follows that when switch A is reversed, when relay G is energized in its reverse direction, and when relay R is energized, the lower blade of signal S¹ and signal S² are cleared. The signals may be placed at stop at any time by restoring the lever L to its neutral position, thereby de-energizing relay G and breaking the clearing circuits for the signals at front contact 76 of relay G.

If the operator wishes to restore the switch to its normal position, he may do so by moving the lever L to its normal position. Current from battery F² then flows through wire 91, normal contact 13—13^a of lever L, wires 25, 32, 24, 23 and 22, back contact 21 of relay B, wires 20 and 19, winding of relay G, wires 18 and 17, winding of relay H, wire 16, normal contact 14—14^a operated by lever L, wire 26, winding of relay J, wires 27, 28 and 29, circuit controller K, and wires 30 and 31, back to battery F². Current thus supplied to relay G energizes this relay in the normal direction, but the magnitude of this current is not sufficient to cause relay H to close. With relay G picked up in its normal direction, current from battery E¹ flows through wires 40 and 39, winding of relay D, wire 38, front contact 37 of relay G, wire 36, normal contact 35 of relay G, and wires 107 and 53 to battery E¹. Relay D therefore is moved to its normal position, whereupon motor M is actuated to restore the switch A to its normal position. During this movement of the switch, contacts 7—8 and 7—9 are successively operated to pick up relay B in the normal direction for brief intervals and to transmit a return indication to relay H, whereby this relay is repeatedly energized to flash lamp 90 twice.

The operation of the apparatus to send a return indication to relay H in response to movements of the switch from reverse to normal is similar to the operation already described in connection with switch movements from normal to reverse and will be understood without further explanation.

When the movement of the switch has been completed, the opening of contact 10—11 interrupts the circuit for motor M, and the level L may then be restored to its neutral position or may be held in its normal position. In the latter case relay G remains closed and current from battery E² flows through wires 33, 41, 54 and 73, front contact 74 of relay R, wire 75, front contact 76 of relay G, wire 77, normal contact 78 of relay G, wire 92, contact 6 operated by switch A, wires 93 and 94, operating mechanism of signal S³ and wires 82, 83, 61 and 40, back to battery E². At the same time, current flows over a branch circuit from wire 93, through wire 95, operating mechanism of the upper blade of signal S¹, and wire 85 to wire 83. Signal S³ and the lower blade of signal S¹ are therefore cleared to permit traffic to move along the stretch W over the switch A in its normal position.

It is sometimes desirable to inform the operator concerning the condition of the track circuit including a switch which is controlled from a remote point. In the present embodiment of my invention I accomplish this result by energizing relay H in its normal direction so that its polar contacts swing to the left when the track circuit including relay R becomes occupied. Thus when relay R becomes de-energized as the result of the entrance of a train into the associated track circuit, current from battery E¹ flows through wires 40, 61 and 60, winding of relay B, wires 59 and 58, back contact 57 of relay R, and wires 96, 50, 51, 52 and 53, back to battery E¹. Under these conditions relay B is energized in the reverse direction so that its polar contacts swing to the right, and due to the opening of back contact 68 of relay B, relay C becomes de-energized. During the brief interval of time that relays B and C are both closed, if lever L is in its neutral or center position, cur-

rent from batteries E¹ and E² flows from battery E², through wires 33, 41 and 97, reverse contact 71 of relay B, wires 23, 32, 25, neutral contact 13—13^a of lever L, wire 86, neutral contact 14—14^a of lever L, wire 16, winding of relay H, wires 17 and 66, front contact 65 of relay C, wire 64, front contact 63 of relay B, wires 62 and 58, back contact 57 of relay R and wires 96, 50, 51, 52 and 53, to battery E¹. The current thus supplied to the relay H energizes this relay in the normal direction so that its polar contacts swing to the left, whereupon current from battery P flows through front contact 87 and normal contact 88 of relay to lamp 89, thereby energizing this lamp to indicate to the operator that the track circuit associated with the switch A is occupied.

It will be noticed that the return indication concerning the condition of the track circuit, is a single impulse and only flashes the lamp 89 once, whereas the lamp 90 is flashed twice during transit of the switch to give a return indication of movement of the switch. It should also be pointed out that the return indication concerning the condition of the track circuit, may be given when the lever L occupies its normal or its reverse position, as well as the neutral position, for which the circuit has just been traced, the only difference being that when the lever L occupies its normal or reverse position relay J is included in the circuit for relay H.

In explaining the operation of relay J, I will first assume that the switch has been moved to its reverse position, and that the lever L is left in its reverse position so that signal S² and the lower blade of signal S¹ have been cleared. With the circuit controller K closed, if a train moves through the track circuit including switch A, the de-energization of relay R interrupts the circuits for these signals at front contact 74 of relay R. All signals are therefore at stop when a train occupies the track circuit. After the train has passed out of the insulated portion of track, relay R again becomes energized, and the signals again move to their clear positions when front contact 74 closes. If circuit controller K is open when the train enters the section, the de-energization of relay R places the signals at stop as before. Furthermore, when the relay R becomes de-energized, relay B picks up, thereby opening 50 at back contact 21 thereof the circuit for relay G. Relay G is therefore disconnected from the control circuit until relay C completes, at its back contact, a branch path around contact 21 of relay B. From the instant when relay B picks up until the instant when relay C releases, relay H is energized in the normal direction for causing switch indication lamp 89 to be lighted. On account of lever L being in the reverse position, relay J is now energized, in series with relay H, in the same direction as before the de-energization of relay R, and relay J therefore remains closed irrespective of whether circuit controller K is open or closed.

I will next assume that switch A has been moved to its normal position, and that lever L has been left in its normal position so that signal S³ and the upper blade of signal S¹ have been cleared. With circuit controller K closed, if a train moves through the track section including switch A, the de-energization of relay R interrupts the circuits for these signals at front contact 74 of relay R, and hence all signals are at "stop" while the train occupies the switch track section. After the train has passed out of this section, relay R again be-

comes energized, and signal S^3 and the upper blade of signal S^1 move to their clear positions when front contact 74 closes. If circuit controller K is open when the train enters the section, the de-
 5 energization of relay R places the signals at stop as before. When relay R becomes de-energized, relay B picks up, thereby opening, at its back contact 21 , the circuit for relay G until relay C completes, at its back contact, the branch path around
 10 contact 21 . Relay H is now again energized in the normal direction from the instant when relay B picks up until relay C releases. On account of lever L being in the normal position, relay J is now energized in series with relay H but in the
 15 opposite direction from its energization before relay R becomes de-energized. This reversal of the direction of energization of relay J causes relay J to open its front contact 99 . When relay R next becomes energized, contact 74 is again closed
 20 and relay B returns to its de-energized position, thereupon closing back contact 21 and connecting relay G with the line wires extending to the lever
 25 L , but relay J is now de-energized and the circuit for relay G is opened at front contact 99 of this relay. Relay G therefore remains in its de-energized position, and the signals remain at stop. Under these conditions therefore, it is necessary to close circuit controller K to pick up relay J . With circuit controller K closed the branch around the front contact 99 of relay J is closed, and relay J picks up. The circuit controller K may then be opened, and the relay J will be subsequently held in its energized position through the branch including its own front contact. The
 30 circuit controller K therefore permits "semi-automatic stick" control of the signals associated with switch A in its normal position, it being necessary after each de-energization of track relay R to close circuit controller K momentarily to allow these signals to be returned to their clear positions. With circuit controller K closed, however, the control of the signals is "semi-automatic non-stick", the signals returning to their clear
 35 positions automatically after the departure of a train from the track circuit.

It should be noted that the impulses of energy supplied to the portion of the circuit including relay H and relay J during a switch movement to its reverse position, that is, the return indication impulses, traverse relay J in a direction opposite to the current normally supplied through this relay from batteries F^1 and F^2 . These return indication impulses therefore open relay J . Now if circuit controller K is open to give semi-automatic stick control of the signals, and if a switch movement is started, the consequent de-energization of relay J by the first return indication impulse will interrupt the control circuit for the switch and prevent the complete transit of the switch. In order to prevent this operation, I have provided a branch around the circuit controller K from wire 29 , through wire 101 , reverse contact 102 of relay H , wire 103 , front contact 104 of relay H , and wire 105 to wire 100 . With this arrangement it will be plain that the branch around circuit controller K is closed for an interval of time after the cessation of the return indication impulse due to the slow-release characteristics of relay H . During this holding interval front contact 99 of relay J is shunted by contacts 102 and 104 of relay H so that the circuit is re-established for relay J , and this relay restores its front contact 99 and permits the operation of the switch to
 45 continue without interruption.

It should be pointed out that while I have, for purposes of illustration, shown only one group of traffic governing devices controlled from a central station, any reasonable number of switches, with their corresponding signals, could be controlled from a single control point, an additional lever L and its associated apparatus being provided for each such group. In such installations it should be pointed out that the wire 32 could serve as a common return wire for the apparatus located at all such groups, only one additional wire, corresponding to wire 17 in the drawing, being required for each additional group.

One advantage of my invention is that control of a switch and its corresponding signals may be accomplished from a remote point over a single pair of line wires, and that this same pair of line wires may be used to transfer return indications from the switch and signals to the control point to inform the operator concerning the condition of the apparatus which he is controlling.

As explained above, the lever L may be operated to one extreme position to actuate the switch, and the lever may then be restored to its middle position without clearing a signal. If the operator then causes a second operation of the lever identical with the operation which moved the switch, a signal will be moved to the proceed position. This feature of causing different operations by repeated identical manipulations of the same control element is not claimed in the present application, but is disclosed and claimed in my copending application, Serial No. 260,619, filed March 10, 1928, for Remote controlling apparatus.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination with a railway traffic governing device, a first polarized relay, means for moving said device to one position or another according as said first relay is energized in the normal or reverse direction, a second polarized relay, a circuit including said first and second relays in series, manually operable means for supplying said circuit with current of one polarity or the other and of sufficient magnitude to energize the first relay but not the second relay, means operating when said device is being operated to supply the portion of said circuit including said second relay with current of sufficient magnitude to operate such second relay, and indication means controlled by said second relay.

2. In combination with a railway traffic governing device, a first polarized relay, means for moving said device to one position or another according as said first relay is energized in the normal or reverse direction, a second polarized relay, a circuit including said first and second relays in series, manually operable means for supplying said circuit with current of one polarity or the other and of sufficient magnitude to energize the first relay but not the second relay, means operating when said device is being operated to supply the portion of said circuit including said second relay but not the portion of said circuit including said first relay with cur-

rent of sufficient magnitude to operate such second relay, and indication means controlled by said second relay.

3. In combination with a railway traffic governing device, a first polarized relay, means for moving said device to one position or another according as said first relay is energized in the normal or reverse direction, a second polarized relay, a circuit including said first and second relays in series, manually operable means for supplying said circuit with current of one polarity or the other and of sufficient magnitude to energize the first relay but not the second relay, means effective when said device is being operated to supply said circuit with current of sufficient magnitude to energize said second relay, and means controlled by said device for at times removing said first relay from said circuit.

4. In combination with a railway traffic controlling device, a first relay for controlling said device, a second relay, a circuit including said two relays in series, manually operable means for supplying the circuit with current to which said first but not said second relay responds, means for at times removing said first relay from said circuit, means controlled by said device for at times supplying the portion of the circuit containing said second relay with current to which such second relay responds, and indication means controlled by said second relay.

5. In combination with a railway traffic governing device, a first polarized relay, means for moving said device to one position or another according as said first relay is energized in the normal or reverse direction, a single pair of line wires extending between said device and a remote point, means for normally connecting said first relay across such line wires, manually operable means located at such remote point for supplying current of one polarity or the other to such line wires, a second relay connected in series with one of such wires adjacent said remote point but requiring a greater current to energize it than is supplied to the relay by said manually operable means, means effective during operation of said device to disconnect said first relay from one line wire and to supply the line wires with current of sufficient magnitude to operate said second relay, and indication means controlled by said second relay.

6. In combination with a railway traffic governing device, a first polarized relay, means for moving said device to one position or another according as said first relay is energized in the normal or reverse direction, a pair of line wires normally connected with said first relay, a manually operable lever, means for supplying said line wires with currents of different polarities or for connecting the wires together depending upon the position of the lever, a second relay connected in one such wire but not responsive to current from the last mentioned means, a third relay arranged to be energized for a brief interval during operation of said device, a fourth relay arranged to be energized only when such third relay is de-energized, means effective when said third and fourth relays are both closed to disconnect said first relay from said line wires and to supply such line wires with current to energize said second relay, and indication means controlled by said second relay.

7. In combination with a railway traffic governing device, a first polarized relay, means for moving said device to one position or another according as said first relay is energized in the

normal or reverse direction, a second polarized relay, a circuit including said first and second relays in series, manually operable means for supplying said circuit with current of one polarity or the other and of sufficient magnitude to energize the first relay but not the second relay, means effective when said device is operating to supply successive impulses of energy to the portion of said circuit including said second relay, and indication means controlled by the second relay.

8. In combination with a railway traffic governing device controlled from a remote point, an indication relay located at such remote point, a second relay located adjacent said device, means effective during operation of the device to energize said second relay repeatedly for brief intervals of time, a slow releasing relay controlled by a back contact of said second relay, and means effective when said second relay and said slow releasing relay are both closed to supply current to said indication relay.

9. In combination, a railway switch, a motor for operating said switch and having a field and an armature, a first contact open only when the switch occupies its reverse position, a second contact open only when the switch occupies its normal position, a first polarized relay, a manually operable lever located at a point remote from the switch, means controlled by said lever for supplying said first relay with current of one polarity or the other, a second polarized relay arranged to be energized in one direction or the other according as the first relay is energized by current of one polarity or the other; a circuit for operating said motor in one direction including a reverse contact of the second relay, said first contact and the armature and field of the motor; and a circuit for operating the motor in the opposite direction including a normal contact of said second relay, said second contact, and the field and armature of the motor.

10. In combination a railway traffic governing device, a first relay for controlling said device, a second relay responsive to the polarity of the current supplied thereto, a circuit including said two relays, means for including in said circuit, a source of current which energizes the first but not the second relay, means responsive to traffic conditions adjacent said device for at times supplying the portion of said circuit including said second relay and said source with current which energizes said second relay with current of one polarity or the other, and indication means selectively controlled by said second relay in accordance with the polarity of the current supplied to such relay.

11. In combination with a railway switch, a manually operable lever located at a point remote from the switch, means including a single pair of line wires extending between the switch and said point for moving the switch to one position or the other depending upon the position of said lever, an indication relay located at said remote point and responsive to the polarity of the current supplied thereto, means effective upon an operation of said switch to supply successive impulses of current of one polarity to said second relay over said line wires, and means responsive to traffic conditions adjacent said switch for at times supplying a single impulse of energy of the opposite polarity to said second relay over said line wires.

12. In combination with a railway traffic controlling device, a first relay for controlling said

- device, a second relay, a circuit for said relays including a front contact of the second relay, a third relay, means for energizing said third relay during operation of said device, such means operating also to open the front contact of said second relay, and a branch around said front contact controlled by said third relay.
13. In combination with a railway switch, a signal governing traffic over the switch, a first relay for controlling said switch and said signal, a second relay, a third relay responsive to the polarity of the current supplied thereto, a circuit including said three relays and a front contact of the second relay in series, means for supplying said circuit with current of sufficient magnitude to operate said first and second relays but not said third relay, a manually operable contact connected in parallel with said front contact, means for at times replacing said first relay in said circuit by a source of current sufficient to energize said third relay but of such character as to open said second relay, and a branch around said front contact including a contact of said third relay.
14. In combination, a railway traffic governing device, a first relay for controlling said device, a second relay, a circuit including said two relays, means for including in said circuit a source of current which energizes the first but not the second relay, means responsive to the condition of said device for at times increasing the amount of current in that portion of said circuit including said second relay to cause the energization of such second relay, and indication means controlled by said second relay.
15. In combination, a railway traffic governing device, two indication relays, a control relay, a circuit including said three relays in series, means controlled by said control relay for governing said device, means controlled by said device for controlling one said indication relay, and means controlled by traffic conditions adjacent said device for controlling the other said indication relay.
16. In combination, an indication relay which becomes energized for a given period of time in a normal direction or for a different period of time in a reverse direction as controlled by a railway traffic governing device, an indication means, and means controlled by said relay for operating said indication means momentarily when said relay becomes energized in the normal direction and also when said relay becomes energized in the reverse direction.
17. In combination, a stretch of railway track including a switch, an indication device responsive to the polarity of current supplied to said device, means controlled by said switch for supplying current of one polarity to said device when said switch is being operated to the normal position and of the same polarity when said switch is being operated to the reverse position, and means controlled by track circuit conditions in said stretch for supplying current of the opposite polarity to said device.
18. In combination, a stretch of railway track including a switch, a polarized indication relay, a track circuit for said stretch including a track relay, a circuit including a front contact of said track relay and a contact operated by said switch for energizing said indication relay by current of a given polarity, and a circuit including a back contact of said track relay for energizing said indication relay by current of the opposite polarity.
19. In a train despatching system for railroads, a transmitter for delivering signals for controlling a governing device at a remote station, indication means adjacent said transmitter selectively controlled in response to traffic conditions at said station, and manually controlled means for at times placing said transmitter under the control of said indication means.
20. In a despatching system for railroads, the combination with a despatcher's office having a signal transmitter comprising a plurality of control circuits each arranged when closed to give a distinctive character to the signal delivered by said transmitter, of indication means associated with said transmitter and supplied with indication signals from a remote point, and a branch for one said control circuit controlled by said indication means.
21. In a despatching system for railroads, the combination with a despatcher's office having a signal transmitter comprising a plurality of control circuits each arranged when closed to give a distinctive character to the signal delivered by said transmitter, of indication means associated with said transmitter and supplied with indication signals from a remote point, means controlled by said indication means and selectively responsive to a particular indication signal for controlling one of said control circuits, and manually controlled means in the despatcher's office for preventing the control of said one circuit by said indication means.
22. In a despatching system for railroads, the combination with a despatcher's office having a signal transmitter comprising a plurality of control circuits each arranged when closed to give a distinctive character to the signal delivered by said transmitter, of manually controlled means for selectively controlling said circuits, indication means associated with said transmitter and selectively controlled from a remote point, and manually controlled means for placing one of said circuits under the control of said indication means.
23. In a centralized traffic control system for railways, a dispatcher's office and a remote station, a track section and a signal governing traffic through said section at the station, control means at the office for clearing said signal when said section is unoccupied, a stick control circuit for said signal including a stick relay and a front contact of said relay as well as a second contact adapted to be opened when the track section is occupied, a non-stick control circuit for said signal including said relay and said second contact but not including said first contact, and manual means at said office for rendering one or the other of said control circuits available at will whereby said signal may optionally be caused to remain at stop or to clear automatically following the movement of a train through said section.
24. In a centralized traffic control system for railways, a dispatcher's office, a track section at a remote station, a railway signal governing traffic through said section, control means at the office for clearing said signal, a holding circuit for said signal comprising a stick relay and its front contact and a control contact, means responsive to the occupancy of said section for opening said control contact to release said stick relay, and manually controllable means at said office for bridging said front contact.
25. In combination with a railway traffic governing device, a control relay, means controlled

5 by said relay for operating said device, a second relay and a movable contact adjacent said device, a single pair of line wires extending from said device to a remote point, manually operable lever contacts at said remote point; a control circuit including said lever contacts, said line wires and the control relay; a first indication circuit including said lever contacts, said line wires, a front contact of said second relay, and said movable contact; a second indication circuit including said lever contacts, said line wires, and a back contact of said second relay; indication means at said remote point included in all said circuits but selectively responsive to the closing of said 10 first or of said second indication circuit, and indicators controlled by said indication means to indicate the de-energization of said second relay or the closing of said movable contact.

15 26. In combination with a section of railway track including a track switch, a control relay for the switch, means controlled by said relay for operating the switch, a track relay for the section, and a movable contact independent of said track relay, a single pair of line wires extending from the switch to a remote point, manually operable lever contacts at said remote point; a control circuit including said lever contacts, said line wires, and the control relay; a first indication circuit including said lever contacts, said line wires, a front contact of the track relay and said movable contact; a second indication circuit including said lever contacts, said line wires and a back contact of the track relay; and indication means at said remote point included in all said circuits but selectively responsive to the closing of said first or of said second indication circuit, an indicator controlled by said indication means to indicate when the track relay becomes de-energized, and a second indicator controlled by said indication means to indicate when said movable contact is closed.

20 27. In combination with a stretch of railway track including a track switch, a control relay for the switch, means controlled by said relay for operating the switch, a track relay responsive to traffic conditions in a portion of said stretch, a single pair of line wires extending from said device to a remote point, a three-position manually operable circuit controller at said remote point; control circuits for governing said control relay and including said line wires, the control relay, a source of energy, and contacts of the circuit controller closed only in one extreme position or the other of said controller; an indication circuit including said line wires, a contact of said track relay, a second source of energy and a contact of the circuit controller closed when said controller is in the mid position; and indication means at said remote point included in all said circuits but selectively responsive to current from said second source of energy to indicate the condition of said track relay at said remote point.

25 28. In combination with a railway traffic governing device, a control relay, means controlled by said relay for operating said device, a first and a second relay adjacent said device, a single pair of line wires extending from said device to a remote point, manually operable lever contacts at said remote point; a control circuit including said lever contacts, said line wires and the control relay; a first indication circuit including said line wires and contacts of said first and of said second relay, a second indication circuit including said line wires and contacts of said first relay and contacts of said second relay closed when said

first named contacts of said second relay are open, and indication means at said remote point included in all said circuits but selectively responsive to the closing of said first or of said second indication circuits to indicate the condition of said relays at said remote point.

29. In combination with a railway traffic governing device, a polarized relay for controlling said device, a control circuit for said relay including a manually movable lever, a stick relay having its winding and a front contact included in said control circuit, an indication relay controlled by said device, and means controlled by said indication relay for at times shunting the front contact of said stick relay.

30. In combination with a railway traffic governing device, a polarized relay for controlling said device, a control circuit for said relay including a manually movable lever, a stick relay having its winding and a front contact included in said control circuit, a slow release relay controlled by said device, and means including a front contact of said slow release relay for at times shunting the front contact of said stick relay.

31. In combination with a railway traffic governing device, a polarized relay for controlling said device, a control circuit for said relay including a manually movable lever, a stick relay having its winding and a front contact included in said control circuit, an indication relay controlled by said device and by track conditions adjacent said device, and means controlled by said indication relay for at times shunting the front contact of said stick relay.

32. In combination with a railway traffic governing device, a polarized relay for controlling said device, a control circuit for said relay including a manually movable lever, a stick relay having its winding and a front contact included in said control circuit, means controlled by traffic conditions adjacent said device for opening said control circuit at times to release said stick relay, an indication relay controlled by said device, and means controlled by said indication relay for at times shunting the front contact of said stick relay.

33. In combination with a railway traffic governing device, a polarized relay for controlling said device, a control circuit for said relay including a manually movable lever, a stick relay having its winding and a front contact included in said control circuit, means controlled by traffic conditions adjacent said device for opening said control circuit at times to release said stick relay, a polarized indication relay controlled by said device, and means including a polar contact of said indication relay for at times shunting the front contact of said stick relay.

34. In combination, a detector section of railway track including a track switch, a polarized control relay for controlling the switch, a control circuit for said relay including the winding and a front contact of a stick relay, a polarized indication relay controlled by the switch and by the track relay for said detector section, and means controlled by said indication relay and selectively responsive to its control by the switch for shunting the front contact of said stick relay.

35. In a remote control system, a detector section of railway track containing a track switch, a polarized relay for controlling the switch; a control circuit for said polarized relay including the winding and a front contact of a stick relay and a second contact adapted to be opened when

the detector section is occupied; a second control circuit for said polarized relay including the stick relay and said second contact but not said front contact; and a manually movable lever for rendering one or another of said control circuits available at will.

36. In combination with a railway traffic governing device, a polarized relay for controlling said device, a control circuit for said relay including a source of energy and manually controlled contacts movable from one control position to another through an intermediate position to reverse said polarized relay, a stick relay having a stick circuit which opens when said contacts are moved from one control position to the other, a slow release relay having a circuit closed in accordance with traffic conditions adjacent said device when said contacts occupy said intermediate position, and a pickup circuit for said stick relay controlled by said slow release relay.

37. In a system for the remote control of a movable device, a manually movable control lever, a control circuit for the device including contacts of said lever closed when the lever is in one extreme position or another, a slow release relay controlled by conditions adjacent said device and having a circuit closed when said lever is in an intermediate position, and means for governing the continuity of said control circuit comprising a stick relay having a stick circuit closed only when the lever is in one extreme position or the other and a pickup circuit controlled by said slow release relay.

38. In a system for the remote control of a movable device, a manually movable control lever, a control circuit for the device including contacts of said lever, a slow release relay controlled by said device, and means for governing the continuity of said control circuit comprising a stick relay having a pickup circuit controlled by said

slow release relay and a stick circuit controlled by said lever.

39. In combination with a stretch of railway track including a track switch, a control relay for the switch, means controlled by said relay for operating the switch, a track relay responsive to traffic conditions in a portion of said stretch, a single pair of line wires extending from said device to a remote point, a three-position manually operable circuit controller at said remote point; control circuits for governing said control relay and including said line wires, the control relay, a source of energy, and contacts of the circuit controller closed only in one extreme position or the other of said controller; an indication circuit including said line wires, a contact of said track relay, a second source of energy and a contact of the circuit controller, and indication means at said remote point included in all said circuits but selectively responsive to current from said second source of energy to indicate the condition of said track relay at said remote point.

40. In combination with a railway traffic governing device, a control relay, means controlled by said relay for operating said device, a first and a second relay adjacent said device, a single pair of line wires extending from said device to a remote point, manually operable lever contacts at said remote point; a control circuit including said lever contacts, said line wires and the control relay; a first indication circuit including said line wires and certain contacts of said first and of said second relay, a second indication circuit including said line wires and other contacts of said first and of said second relay, and indication means at said remote point included in all said circuits but selectively responsive to the closing of said first or of said second indication circuits to indicate the condition of said relays at said remote point.

HERBERT A. WALLACE.
